JOHN FREDERICK HOWARTH, OF NEW YORK, N. Y.

MEANS FOR COOLING ENGINES AND PURIFYING LUBRICANTS

Application filed February 27, 1928. Serial No. 257,324.

My invention relates to means for purifying the lubricating oil of an engine, and particularly an internal combustion engine, by removing diluents therefrom, and at the same time substantially cooling the oil and the engine itself. Incident to the purification of the lubricant, combustible parts of the diluents are conveyed to the engine cylinders and burned, thus realizing the fuel value of the diluents which otherwise would be lost.

In its broader aspect the invention comprises means for continuously drawing air into the engine crank case through a convenient opening such as the ordinary breather fitting, and removing this air which in its passage through the crank case takes up vaporous material therein including fractions of the engine fuel which have found their way into the crank case past the pistons, some fractions of the lubricant, and water vapor produced by combustion. This vapor laden air hereinafter termed "vapors" is taken from a point in the crank case substantially remote from the air entrance and conveyed to a condensing chamber in which the heavier fractions of the vapors are condensed, these heavier fractions including portions of the lubricant, and the more volatile fractions are conveyed from the condensing chamber to the engine intake manifold, in which the low pressure provides the means for producing the circulation of air and vapor through the crank case and manifold to the engine. The combustible parts of the material removed from the crank case are thus returned to the engine for burning along with the fresh charge. The condensing chamber preferably includes means automatically operated by variations in the manifold pressure produced by variations of throttle position or otherwise, to control the flow of air and vapors and also effect the return at intervals to the crank case of condensate in the condensing chamber. The practically continuous circulation of cool atmospheric air through the crank case materially reduces the temperature therein and makes the lubricant more effective.

The characteristics and advantages of the invention are further sufficiently explained in connection with the following detail description of the accompanying drawings, which illustrate one representative embodiment. After considering this example, skilled persons will understand that many variations may be made without departing from the principles involved, and I contemplate the employment of any structures that are properly within the scope of the appended claims.

Fig. 1 is a side elevation of a typical motor vehicle engine, with oil purifying and cooling mechanism embodying the invention in one form, applied thereto;

Fig. 2 is a vertical section of the oil purifying mechanism on line 2—2 of Fig. 1.

The purifying or condensing apparatus, aside from pipe connections and other appendages, consists of a condensing chamber 1 having an intake fitting or pipe connection 2 at the bottom and also having a cap 3 provided with an outlet fitting or pipe connection 4. The intake fitting is connected by a pipe 5 to a port 6 in the crank case C of an engine E at a point preferably remote from the breather B which ordinarily provides for movements of air into and from the crank case caused by piston movements and temperature variations. The outlet fitting 4 is connected by a pipe 7 to the engine intake manifold M, preferably at a point above the throttle.

The cap 3 is detachably secured as by screws 8 and also retains in position the flange 9 of a cylinder 10 having at its mid-length an annular channel 11 communicating with a port 12 affording connection between the cylinder and the interior of the condensing chamber 1, under control of a piston 13. The upper end of cylinder 10 communicates with the discharge connection 4, and a spring 14 urges the piston to its lower position as shown. The piston is connected to the upper end of a rod 15 which passes through an aperture 16 in the bottom of the cylinder, this aperture being formed as a valve seat in cooperation with a tapered valve formation 17 on the rod at

the base of the piston. The diameter of the rod just below the valve portion 17 is smaller than such valve portion so that when the piston rises communication is established between atmosphere and the interior of the condensing chamber through a port 18 in flange 9, and a passage 19 leading to the bottom of the cylinder.

A portion 20 of the piston rod is fixedly secured in the upper end of a pipe 21, the lower end of which has a sliding fit in a counterbore 22 in the intake connection 2. In the lower end of the pipe are ports 23 so dimensioned that when the piston is in its lower position as shown the ports are closed by the wall of the counterbore, and when the piston rises substantially the ports establish communication between the lower part of the condensing chamber and the intake fitting 2 for the return of condensate into the engine crank case through pipe 5.

The lower portion of the piston rod is formed as a stem 24 of reduced diameter and this may have a conical lower end 25. Substantially at the top of the reduced stem portion of the rod, ports 26 are provided in pipe 21 leading to a cylinder chamber 27 about the upper end of the pipe, this chamber being provided by a sleeve 28 fitting the pipe below the ports and having its upper end open to produce an annular vapor flow which is baffled by the concave lower face of a plate 29 formed as a part of a sleeve 30 secured on the piston rod at the upper end of pipe 18.

Désirably, and especially for use in starting the engine, a throttle valve 35 is placed in the outlet fitting, the shaft of this valve having a lever arm 36 to provide for a link connection (not shown) to a control device convenient to the driver.

Under normal operating conditions, that is, say, when the engine is running with substantially open throttle and fair speed under a moderate load, the special throttle 35 in the condensing appliance is maintained in open position and the degree of pressure in the engine manifold M which at such time is equivalent to say from approximately 3" to 11" mercury gauge, produces a flow of atmospheric air through the breather B into the crank case, where the air takes up from the mist of oil produced by piston and crank movements, the vaporous parts thereof including fractions of the fuel, some lighter fractions of the lubricant, and water vapor, and the vapors thus produced are drawn through pipe 5 and fitting 2 and through the interior of pipe 21. At this time on account of the stated manifold pressure which is insufficient to overcome the pressure of spring 14 and the weight of the piston and connected parts, the piston with its rod and pipe 21 are in their lower positions. The only line of egress from the chamber 1 is

therefore through port 12 to the cylinder above the piston and so through the outlet fitting and pipe 7 to the engine manifold. The rate of vapor flow in the pipe is retarded by stem 24 and the vapor flows through ports 26 and upward through the cylinder chamber 27 and strikes the curved baffle face 29 and is thus deflected outward and downward into contact with the inner wall of the chamber, which is sufficiently cooled by contact with exterior or pure air to produce condensation of the heavier fractions of the vapors. The upward air flow along the wall causes this condensate or liquid to flow slowly downward to the bottom of the chamber and also produces intimate contact with the liquid of the moving vapors, sufficient for removal of substantially all of the volatiles including the fuel fractions, while the lubricant fractions are condensed and retained temporarily at the bottom of the chamber. Finally the vapors charged with the fuel fractions passes to the engine manifold for reintroduction into the cylinder. When the vacuum in the engine manifold is substantially increased, as for example when the engine is idling with nearly closed throttle, the resulting lower pressure in pipe 7 is sufficient to raise piston 13 against the force of its spring, thus establishing communication between the interior of chamber 1 and external or pure air through the passages 18 and 19 and the valve opening 16. At the same time port 12 is closed by the piston thus preventing any air flow through the purifying device to the engine manifold, or in other words preventing any undesired dilution of the engine charge under the stated condition of operation. At the same time the lower end of pipe 21 is raised sufficient to permit condensate in the bottom of the chamber to return to the engine crank case through ports 23 and pipe 5.

The special throttle 35 is desirably closed when the engine is started, especially if the engine is cold, thus preventing undesired dilution of the engine charge in starting; or, as otherwise stated, preventing any interference with the established carburetor action, or effect of the carburetor choke, etc.

It thus appears that the invention in its preferred form includes means for automatic self-regulation, that is the air circulation and purification of the engine oil is carried on under all ordinary or normal operating conditions of the vehicle, and under abnormal conditions as when the engine is idling or starting, the action is interrupted in such manner as to prevent interference with proper carburation at such time.

What I claim is:

1. Apparatus of the character described comprising a condensing chamber, a connection from an intake part thereof to an engine

crank case, and a connection from a discharge part of the casing to the engine intake manifold, and means for controlling vapor flow through the condensing chamber, said means being under control of pressure in the engine intake manifold.

2. Apparatus of the character described comprising a condensing chamber, a connection from an intake part thereof to an engine crank case, and a connection from a discharge part of the casing to the engine intake manifold, and means for controlling vapor flow through the condensing chamber, said means being under control of pressure in the engine intake manifold, and including a piston subjected at one side to manifold pressure and at the other side to substantially atmospheric pressure, and valve means controlled by the piston.

3. Apparatus of the character described comprising a condensing chamber, a connection from an intake part thereof to an engine crank case, and a connection from a discharge part of the casing to the engine intake manifold, and means for controlling vapor flow through the condensing chamber, said means being under control of pressure in the engine intake manifold, and including a piston subjected at one side to manifold pressure and at the other side to substantially atmospheric pressure, and valve means controlled by the piston, said valve means serving to open and close communication between the chamber and atmosphere.

4. Apparatus of the character described comprising a condensing chamber, a connection from an intake part thereof to an engine crank case, and a connection from a discharge part of the casing to the engine intake manifold, and means for controlling vapor flow through the condensing chamber, said means being under control of pressure in the engine intake manifold, and including a piston subjected at one side to manifold pressure and at the other side to substantially atmospheric pressure, and valve means controlled by the piston, said valve means serving to open and close communication between the chamber and atmosphere, and also to control communication between a lower part of the chamber and the connection leading to the engine crank case.

5. A condensing apparatus for purposes described comprising a chamber, an intake fitting at the bottom thereof adapted to be connected with an engine casing, an outlet fitting at the top of the chamber adapted to be connected to the manifold of the engine, a cylinder having its upper end communicating with the outlet fitting, a port in the cylinder wall affording communication with the chamber, a piston in the cylinder, a piston rod connected to said piston, a pipe connected to and movable with the piston rod and having its lower end communicating

with the intake fitting, and means including a baffle for directing vapors from the pipe toward the chamber walls.

6. A condensing apparatus for purposes described comprising a chamber, an intake fitting at the bottom thereof adapted to be connected with the crank case of an engine, an outlet fitting at the top of the chamber and adapted to be connected with the manifold of the engine, a cylinder having its upper end communicating with the outlet fitting, a port in the cylinder wall affording communication with the chamber, a piston in the cylinder, a piston rod connected with the piston, a pipe connected to and movable with the piston rod and having its lower end communicating with the intake fitting, and means including a baffle for directing vapors entering through the pipe toward the chamber walls, the piston also having a valve cooperating with a seat in the lower part of the cylinder, to control communication between the interior of the chamber and atmosphere.

7. A condensing apparatus for purposes described comprising a chamber, an intake fitting at the bottom thereof adapted to be connected to the crank case of an engine, an outlet fitting at the top of the chamber adapted to be connected with the manifold of the engine, a cylinder having its upper end communicating with the outlet fitting, a port in the cylinder wall affording communication with the chamber, a piston in the cylinder, a piston rod connected with the piston, a pipe connected to and movable with the piston rod and having its lower end communicating with the intake fitting, and means including a baffle for directing vapors from the pipe toward the chamber walls, the piston rod having a reduced lower end within said pipe.

8. A condensing apparatus for purposes described comprising a chamber, an intake fitting at the bottom thereof and adapted to be connected with the crank case of an engine, an outlet fitting at the top of the chamber and adapted to be connected with the manifold of the engine, a cylinder having its upper end communicating with the outlet fitting, a port in the cylinder wall affording communication with the chamber, a piston in the cylinder, a piston rod connected with the piston, a pipe connected to and movable with the piston rod and having its lower end communicating with the intake fitting, and means including a baffle for directing vapors from the pipe toward the chamber walls, the pipe having ports opposite the upper end of said reduced rod portion, and means about the pipe for directing air issuing from the ports upward and against the baffle.

9. A condensing apparatus for purposes described comprising a chamber, an intake fitting at the bottom thereof and adapted to be connected with the crank case of an en-

- gine, an outlet fitting at the top of the chamber and adapted to be connected with the manifold of the engine, a cylinder having its upper end communicating with the outlet fitting, a port in the cylinder wall affording communication with the chamber, a piston in the cylinder, a piston rod connected with the piston, a pipe connected to and movable with the piston rod and having its lower end communicating with the intake fitting, and means including a baffle for directing vapors from the pipe toward the chamber walls, and a spring urging the piston to downward position.
- 10 10. A condensing apparatus for purposes described comprising a chamber, an intake fitting at the bottom thereof and adapted to be connected to the crank case of an engine, an outlet fitting at the top of the chamber and adapted to be connected with the manifold of the engine, a cylinder having its upper end communicating with the outlet fitting, a port in the cylinder wall affording communication with the chamber, a piston in the cylinder, a piston rod connected with the piston, a pipe connected to and movable with the piston rod and having its lower end communicating with the intake fitting, and means including a baffle for directing vapors from the pipe toward the chamber walls, and a movable valve in the outlet fitting to shut off connection between the engine manifold and the condensing chamber.
- 20 25 30 35

Signed at New York city, in the county of New York and State of New York this 9th day of November A. D. 1927.
